RICHARD H. RICE, OF NEWPORT, RHODE ISLAND.

Design No. 3,424, dated March 23, 1869.

DESIGN FOR A TRADE-MARK.

The Schedule referred to in these Letters Patent and making part of the same.

To all whom it may concern:

Be it known that I, RICHARD H. RICE, of the city and county of Newport, in the State of Rhode Island, have originated and designed a new Design for a Trade-Mark, of which the following is a full, clear, and exact description, reference being had to the accompanying specimens, making a part of this specification.

The design is intended as a distinctive trade-mark for a medicated lozenge of my composition, and is to be borne upon the label accompanying the package of the same.

It consists of the picture of a bee-hive surmounting the words, "Dr. R. H. Rice's Neuralgia and Rheumatic Magic Lozenge," or equivalent descriptive words.

What I claim as my invention, and desire to secure by Letters Patent, is—

The design for a trade-mark label herein set forth.

RICHARD H. RICE.
